UNITED STATES PATENT OFFICE

2,533,850

UTILITY HANDBAG HAVING DOUBLE COMPARTMENT WITH INDIVIDUAL CLOSURES AND INDEPENDENTLY ACCESSIBLE BOTTOM POCKETS

Frances P. Syracuse, Los Angeles, Calif.

Application September 13, 1947, Serial No. 773,747

1 Claim. (Cl. 150—34)

1

The present invention relates to handbags, and more particularly to the type of handbag used to carry diapers, bottles, and other articles required for the care of an infant while traveling or away from home.

The principal object of the invention is to provide a new and useful handbag having separate moisture-proof compartments, one of which is adapted to receive fresh diapers or other clothing, another being for damp or soiled diapers, and still others being provided to hold bottles or other equipment.

Another object of the invention is to provide a handbag having a plurality of compartments, each of which is accessible from the outside, independently of the others, through separate slide fastener closures of the type known popularly as "zippers."

A further object of the invention is to provide a handbag having separate compartments for fresh and soiled diapers, and still other compartments at the ends of the bag for holding bottles in an upright position, said bottle-holding compartments being accessible from the outside of the bag through slide fasteners in the ends thereof without opening the diaper-holding compartments of the bag. Such a feature is particularly advantageous when traveling in public conveyances or when in congested public areas, since it eliminates the need for exposing the contents of the bag, and makes it possible to get at the bottle without searching through the interior of the bag. In addition to the convenience mentioned, such segregation of the bottles from the other contents of the bag is desirable because it prevents contamination of the nipples by soiled diapers, and provides positive assurance that the nipples will remain sterile until used.

These and other objects and advantages of the invention will become apparent to those skilled in the art upon consideration of the following detailed description of the preferred embodiment thereof, reference being had to the accompanying drawings, wherein:

Figure 1 is a perspective view of a handbag embodying the principles of the invention, the slide fasteners being shown in the partially opened condition to reveal a bottle in one of the end compartments;

Figure 2 is an enlarged transverse vertical section through the same, taken along the line 2—2 in Figure 1;

Figure 3 is a longitudinal vertical section, taken at 3—3 in Figure 1; and

Figure 4 is an enlarged fragmentary sectional

2

view, taken through the top portion of the handbag.

In the drawings, the reference numeral 10 designates the handbag in its entirety, which is seen to comprise a rectangular body having a carrying strap 11 attached to the top end portions thereof. The handbag 10 is made up of an outer covering of fabric or sheet plastic material, suitably cut and stitched together to form sides 13 and 14, a flat bottom 15, and ends 16. The top of the bag is formed by the inwardly turned top edges of the side panels 13 and 14, which are stitched at 20 to the outer tapes 21 and 22, respectively, of two laterally spaced "zippers" 23 and 24. The 15 "zippers" 23 and 24 are completed by a third tape 25 disposed between the tapes 21 and 22, and attached to the free edges of the three tapes are teeth 26 which are adapted to be interlocked by means of slides 30, in a manner well known in the art.

The inside of the bag is lined with a moisture-proof lining 31, preferably of plastic sheeting, which is secured at its outer top edges by the stitching 20. A partition 32 divides the interior 25 of the bag into two separate compartments 33 and 34, one of which is for the purpose of holding clean diapers or clothing, and the other being for the purpose of receiving damp or soiled articles. The partition 32 is preferably formed by two panels 35 and 36 of the moisture-proof plastic sheeting, said panels being sewed together and to the lining 31 at 40, along the bottom, of the bag, and being stitched at 41 to the tape 25 along the center line thereof. The two panels 35, 36 35 enclose a compartment 42 which may be used to hold cosmetics and other articles usually carried in a personal handbag. The compartment 42 is reached through a longitudinally extending opening in panel 35, having a "zipper" 43 along the edges thereof. A rectangular strip 47 of cardboard or other composition is secured in the bottom of the bag between the liner 31 and portion 15, to stiffen the bottom of the bag and hold it to shape.

45 The ends 16 of the bag are formed with vertically extending openings 44 having "zippers" 45 along the edges thereof, whereby the openings can be closed. Attached to both sides of each of the openings 44 along the inside edges thereof, and 50 to the top and bottom corners of the bag, are sections 46 of plastic sheeting forming pockets or compartments 50 which are adapted to receive nursing bottles 51, and hold the same erect.

From the foregoing, it will be seen that the handbag 10 provides separate, moisture-proof

compartments 33 and 34 for holding clean dry articles in one of them, and damp or soiled articles in the other. Each of the compartments 33, 34 is accessible from the outside through its own "zipper" closure 23 or 24 in the top of the bag, making it possible to get into either compartment without exposing the contents of the other. The inside compartment 42 provides a receptacle for cosmetics or other personal effects of the mother, and eliminates the need for a separate handbag to carry the same. The two bottle pockets 50 in the ends of the bag provide convenient receptacles for holding nursing bottles in erect position, said bottles being segregated from the other articles in the bag so that the nipples thereof cannot become contaminated. The separate "zippers" 45 for each of the bottle compartments make it possible to get at either of the bottles without opening the diaper compartments 33 and 34, which is a particularly convenient feature when it becomes necessary to remove or replace a bottle in congested public areas, or where the light is poor.

In addition to the many advantages mentioned above, the handbag 10 is singularly well adapted for use as a beach bag for carrying towels, bathing suits, bottles of lotion, and the like. Here again, the moisture-proof lining of the bag permits damp and dry articles to be segregated from one another, while bottles of sun tan lotion are carried in upright position in the bottle compartments 50 and are conveniently accessible through the "zipper" closures 45. Cosmetics, cigarettes, currency, and the like can all be carried in the inner compartment 42 without being dampened by wet bathing suits and towels in the compartments 33 and 34.

While I have shown and described in considerable detail what I believe to be the preferred embodiment of my invention, it is to be understood that such details are merely illustrative, and that various changes may be made in the shape and arrangement of the several parts without departing from the scope of the invention, as defined in the appended claim.

I claim:

A handbag for carrying clean and soiled infant's diapers and nursing bottles, comprising a rectangular body having horizontal top and bottom edges, and vertical sides and ends, said top

edge having two laterally spaced, longitudinally extending openings formed therein separated by a narrow strip of material, a waterproof partition panel within said body dividing the interior thereof into two laterally spaced compartments, one of which is adapted to receive clean diapers, and the other being adapted to receive soiled diapers, the top edge of said panel being attached to the underside of said strip of material, closure means for said openings comprising rows of slide fastener teeth attached to the material along opposite edges of each of said openings, the two companionate rows of teeth along the side of each of said openings being adapted to intermesh with one another to close the opening, slide means associated with each of said pairs of intermeshing rows of teeth, said slide means being selectively operable from the outside of the sandbag to open either one of said compartments without opening the other, each of said ends of said body having a vertically extending opening formed therein, intermeshing slide fastener teeth attached to the material along both edges of each of said end openings, whereby the openings can be closed, waterproof plastic sheeting attached to the inside of said handbag body along the inside edges of said end openings, said plastic sheeting forming pockets within the interior of said body in which nursing bottles can be carried entirely separate from said diaper compartments and protected from contamination, and a slide for operating each of said end slide fasteners from the outside of the bag to provide access to either of said bottle pockets without opening said diaper compartments.

FRANCES P. SYRACUSE.
